UNITED STATES PATENT OFFICE.

AXEL HERMAN OLSSON AND HENNING BERNHARD MATHIAS PLEIJEL, OF STOCKHOLM,
SWEDEN.

TELEPHONE-REPEATER.

1,189,728.

Specification of Letters Patent.

Patented July 4, 1916.

Application filed November 28, 1914. Serial No. 874,533.

To all whom it may concern:

Be it known that we, AXEL HERMAN OLSSON, engineer, and HENNING BERNHARD MATHIAS PLEIJEL, professor, both subjects 5 of the King of Sweden, citizens of Sweden, and respectively residing at Bergsgatan 16^B and Brunnsgatan 2, Stockholm, in the Kingdom of Sweden, have invented certain new and useful Improvements in Telephone-Re- 10 peaters, of which the following is a specification.

As is well known, so-called telephone repeaters have been used in telephone apparatus for the purpose of separating two 15 lines, so that direct current, or a current comparable thereto, does not pass over from the one line to the other. For instance, telephone repeaters are used for connecting single lines with double lines. All such tele- 20 phone repeaters as hitherto constructed consist of two windings, which are wound upon a common iron core common to both. In re- 25 cent times extensive use has been made of such telephone repeaters. They have, for instance, been employed to connect lines of different kinds (cable line and free line) for the purposes of removing to the greatest possible degree the reflection of telephone waves, which would otherwise arise. Fur- 30 ther, such telephone repeaters have been extensively used in combination lines for telephony and telegraphy. In proportion as the length of telephone lines has been increased, it has become necessary to improve 35 these telephone repeaters in every respect, so that they may repeat with the slightest possible loss the high frequency speech currents as well as the currents with lower period numbers, which are used for calling. 40 Two telephone repeaters of the "Western Electric" type, when inserted in a line, offer a resistance to the arriving speech currents equal to that of three miles of the "British Standard" cable, and these telephone repeaters are considered the best now available. 45 The telephone repeaters of the British post office offer, on the contrary, to the arriving speech currents a resistance equal to that of 10 to 12 miles of the 50 "British Standard" cable. With regard to the transmission of calling currents, however, the conditions are reversed, that is to say, the telephone repeater of the British post office is superior to that of the "West- 55 ern Electric" type, and as hereinafter fur-

ther stated, this results from the principle of their construction (two windings upon the same iron core), which always entails the consequence that a reduction of the speech current loss affects the calling cur- 60 rents and vice versa.

In an article published in "*Compte Rendue de la IIe Conference Internationale des Techniciens des Telegraphes et des Telephones de l'Europe, Paris 1910*" with the 65 title "*Sur le calcul des enroulements d'un transformateur telephonique*", are explained the conditions under which the best effect of a telephone repeater is obtained. From this article, it will be understood that these 70 conditions depend to the greatest extent upon the number of periods of the currents. If, accordingly, the repeater is constructed in such a manner that it is as efficient as possible for speech currents, its capacity for 75 transmitting calling currents is reduced in an essential degree and vice versa. From the same article, it will be seen that the telephone repeater can not only be constructed in such a manner that the losses are reduced, 80 but can also be constructed so as to effect a strengthening of the arriving currents, when currents are being dealt with whereof the respective number of periods lie between 85 certain limits. Practical tests made with correspondingly constructed telephone repeaters have fully verified the said theory.

An ideal repeater for telephonic purposes should have such characteristics that it has an improving action upon the speech cur- 90 rents as well as upon the calling currents used in telephone traffic. As above stated, it is impossible to obtain this effect by pur- 95 suing the principle hitherto followed; namely, two windings on a core common to both. To solve the problem, we employ a combination of two telephone repeaters, one of which is constructed so as to act in the best possible way for the speech currents, while the other is calculated to act in the 100 best way for the calling currents. It is not sufficient however, to merely connect these two coil devices together, seeing that, if they be coupled in series, the combination would act as a repeater, acting very inef- 105 ficiently both for the speech currents and for the calling currents. The same condition would, of course, exist if the coils were coupled in parallel. The coils must be so arranged that the action of the one 110

coil will not be affected by the other coil, and in order to obtain this object, we utilize the property inherent to a condenser of acting in different ways upon high frequency 5 and low frequency currents. As is well known, the impedance of a condenser is reduced in proportion as the number of periods increases. A condenser, therefore, which acts as a high resistance for the low 10 frequency calling currents, transmits the speech currents without difficulty.

In the accompanying drawings, Figure 1 is a diagrammatic view illustrating a system arranged according to our invention; 15 Fig. 2 being a similar view illustrating a modification thereof.

To attain a complete balance, the two windings of the speech current coil are each subdivided into two halves arranged one on 20 each side of the calling current coil E or E^1 . The primary winding of the speech current coil thus consists in the system shown in Fig. 1, of A, B and C, D; the secondary winding of A^1 , B^1 and C^1 , D^1 . Between B 25 and C and between B^1 and C^1 is inserted a condenser F or F^1 of corresponding capacity.

To adapt the system for use in duplex lines, the middle point of the secondary 30 winding E^1 of the calling current coil is taken out. The speech currents now select, on account of their high number of periods, the path A, B, F, C, D, in the primary circuit and the path A^1 , B^1 , F^1 , C^1 , D^1 in 35 the secondary circuit. The speech current coil may, accordingly, be constructed exclusively for currents of a number of periods, which lie between the limits for the speech currents. According to the theory, 40 this coil will then be constructed with a comparatively small number of windings and with a core of finely-divided iron. The coil may, if desired, be specially calculated for the line in order to obtain the best possible result. In the case of the calling 45 currents, on the contrary, the condensers act as high resistances, whereupon these currents select the paths A, B, E, C, D, and A^1 , B^1 , F^1 , C^1 , D^1 . In order to obtain a good 50 transmission of the calling currents, the

calling current coil may thus be constructed so as to act upon the transmission in the most favorable manner. According to the theory, this coil should be wound with a great number of windings and be provided 55 with an iron core having a slight magnetic resistance. The iron core is thus constructed according to those principles usually followed in constructing transformers. The same effect, namely that the speech 60 current coil and the calling current coil may each be constructed and act for one kind of current independently of each other, can also be obtained by combining them with the condensers in the manner shown 65 in Fig. 2.

A, B, and C, D are the primary windings, A^1 , B^1 and C^1 , D^1 the secondary windings of the speech current coil.

G, H is the primary winding and G^1 , H^1 70 the secondary winding of the calling current coil.

F and F^1 are the two condensers.

In view of the great impedance of the windings G, H and G^1 , H^1 for the speech 75 currents, these latter here select the paths A, B, F, C, D, and A^1 , B^1 , F^1 , C^1 , D^1 . The calling currents, on the contrary, to which the condensers offer a high resistance pass through G, H, or G^1 , H. 80

We claim:—

1. A telephone repeater for speech-as well as for calling-currents, embracing two induction-coils whereof one is adapted for working with the speech-current and the other for working with calling-currents.

2. A telephone repeater comprising two induction-coils wherein the primary windings and the secondary windings are respectively connected up in series, and where in the calling-current source is bridged by a capacity. 90

In testimony whereof we have affixed our signatures in presence of two witnesses:

AXEL HERMAN OLSSON.

HENNING BERNHARD MATHIAS PLEIJEL.
